MEAT PACKAGING MACHINE

James R. Tannehill and Robert D. Moore, both of P.O. Box 108, Traverse City, Mich., and Frederick A. Zaenkert, Greenhills, Ohio; said Zaenkert assignor to said Tannehill and said Moore

Filed June 20, 1960, Ser. No. 37,499
16 Claims. (Cl. 53—123)

This invention relates to improvements in meat packaging machines. The machine of the present invention is, in certain respects, an improvement upon the machine, the subject matter of the application for patent of James R. Tannehill and Robert D. Moore, Serial No. 810,461, filed May 1, 1959 and entitled "Apparatus for Use in and Method of Packaging Food Products and the Like."

The principal objects of this invention are,

First, to provide means for applying and supporting a strip of flexible sheet material to a series of parallel slicing knives.

Second, to provide a machine which automatically extends a strip of flexible material of correct length for successive operations as each package or body of meat is divided and advanced with the sheet pressed into dividing relation to the meat mass.

Third, to provide a packaging machine which will automatically conform the strip or length of flexible sheet product separating material to the surfaces of a plurality of parallel dividing knives, then thrusting the knives with the sheet thereon into the product being sliced, retracting the knives leaving the sheet in dividing relation to the product, and then advancing the divided package for a successive operation on a similar packaged product.

Fourth, to provide a plurality of parallel meat dividing knives with a corresponding number of suction chambers separated by automatically actuated valves for successively drawing a sheet or strip of flexible dividing material into close conformity to the knives and the surfaces between them by means of suction applied to the suction chambers in succession.

Other objects and advantages of the invention will be apparent from a consideration of the following description and claims. The drawings, of which there are three sheets, illustrate a highly practical form of the machine of the invention.

FIG. 1 is a fragmentary side elevational view of the machine illustrated at the end of a packaging cycle.

FIG. 2 is a fragmentary end elevational view of the machine.

FIG. 3 is a fragmentary transverse vertical cross sectional view taken along the plane of the line 3—3 in FIG. 1.

FIG. 4 is a fragmentary end elevational view of the control switches and meat separating head as viewed from the plane of the line 4—4 in FIG. 1.

FIG. 5 is a fragmentary cross sectional view through the automatic vacuum valve taken along the plane of the line 5—5 in FIG. 3.

FIG. 6 is a schematic wiring and piping diagram of the electric, pressure and vacuum circuits of the machine.

FIG. 7 is an enlarged fragmentary sectional view illustrating structural details of the slicing head member and the means for wrapping and supporting the sheet material thereon as a preliminary step to the slicing actuation of the head member.

In the copending application identified above, there is disclosed and claimed a machine and method for dividing a mass of meat into a plurality of parallel blocks or masses of meat by pressing flexible sheet material into the meat by a series of parallel knives reciprocated into the mass of meat. The present invention includes a ma-

2

chine mounted on a suitable framework designated generally by the numeral 1 and provided with conveyor chains 2 and 3 trained in loops around driving sprockets 4 and idler sprockets 5. The chains 2 and 3 carry meat package supporting slats 6 and spaced series of sheet stock supporting blocks 7 to advance the product to the right, as shown in FIG. 1. A driving motor 8 operating through a gear box 9 is connected by the chain 10 to an overrunning clutch 11 mounted on the drive shaft 12 of the driving sprockets 4. The motor 8 and clutch 11 function to advance the conveyor chains as will be described, but the overrunning clutch 11 permits advance of the chain independently of the motor during a portion of the cycle of the machine, as will be described.

Supported over an intermediate portion of the conveyor by upright supports 13 and a top panel 14 is a cylinder 15 having a reciprocable piston rod 16 connected to the reciprocable cutter head 17. The cutter head 17 includes a suction chamber 18 divided into a series of sub-chambers by partitions 19. The partitions are provided with automatic valves 20 which open successively and automatically, as will be described. Mounted on the underside of the chamber 18 and under the partition plates 18 are a plurality of transversely extending meat slicing or dividing knives 21 which are approximately as wide as the mass of meat to be divided. Ports 22 provide communication between the sub-chambers of the vacuum chamber 18 and the spaces between the adjacent knives 21.

Supported over the conveyor at the front of the head 17 is a roll 23 of flexible separating material. Synthetic polyolefin is a desirable material. The sheet 24 is trained over a guide roller 25 and carried forwardly underneath the knives 21. A loading station arranged to receive a fiberboard carton with a slab of meat therein of the desired thickness is indicated at 26 just behind the incoming sheet or web. A flight plate 27 on the conveyor slats functions to advance the container with the product to be divided underneath the knives 21. Prior to entry of the product under the knives the sheet 24 is supported in close proximity to the knives by a series of previously described blocks 7 as shown in FIGS. 1 and 3.

Positioned underneath the conveyor and between the uprights 13 is a horizontally disposed pressure actuated cylinder 28 having a reciprocable piston rod 29 with a pawl 30 on its rear end. The pawl 30 is engageable behind a lug 31 on the center of the conveyor and functions to advance the conveyor independently of the motor 8 to advance the new carton of meat from the loading station 26 to underneath the knives 21. Reference may now be had to the circuit diagram in FIG. 6 in connection with FIG. 1. After the new box of meat is inserted in the loading station 26, the operator presses the manual switch 32 to complete a circuit through the safety switch 33 and the solenoid 34 of a valve 35 that activates the cylinder 28 to advance the piston rod 29 and the new carton of meat to underneath the knives 21. The safety switch 33 is held closed by a tappet 36 carried on a bar 37 reciprocated with the head 17 and is closed only in the raised position of the head so that the conveyor and package of meat cannot be advanced until the knives are raised.

Advancing motion of the conveyor to position the product underneath the knives brings a tappet 38 on the chain 2 into contact with a safety switch 39 to close the switch and signal or condition the circuit for further operation of the machine. With the switch 39 closed and the cylinder 28 in its fully actuated position to locate the product under the head 17, the operator closes the push button switch 40 completing a circuit through the solenoid valve 41, conductor 42 and switch 39 to the conductor 43 to start the piston rod 16 and head 17 downwardly. It will be understood that the sheet of separating

material had previously been conformed to the knives 21 at the end of the preceding cycle as will be described and that the sheet is held in the recesses between the knives by suction in the head 17.

The initial downward movement of the head 17 and the switch bar 37 carried thereby opens the switch 33 to deenergize the solenoid 34 and cut off the advancing pressure to the cylinder 28. Near the end of the down stroke of the head 17 and the switch bar 37, a tappet 44 engages and closes the switch 45 completing a circuit through the conductor 46 and solenoid 47 to close the valve 48 and cut off the suction to the head 17 and admit atmospheric pressure to the pipe 49. Continued and final movement of the head and switch bar 37 downwardly causes a tappet 50 to engage and close a switch 51 which completes a circuit from the conductor 46 to a conductor 52 and the solenoid valve 53 and conductor 54 to close off the supply of fluid pressure to the top of the cylinder 15 and admit pressure to the bottom of the cylinder and immediately start the elevation of the head 17. In this condition the flexible sheet 24 is pressed in folds transversely through the block of meat in the package and the knives are retracted from the folds of the sheet. At the completion of the upward stroke of the switch bar 37 a pivoted pawl 55 momentarily strikes and closes a switch 56. The switch 56 is in series with and energized from a normally closed limit switch 57 through the conductor 58 and when closed energizes the conductor 59 and the solenoid 60 of a relay switch. The energization of the solenoid 60 closes a first switch 61 that energizes the motor 8 to drive the conveyor through the overrunning clutch 11 and simultaneously closes a switch 62 establishing a holding circuit from the switch 57 through the conductor 63 and switch 62 to the solenoid 60 so that the motor 8 continues to operate and advance the newly separated package of meat from underneath the raised head 17.

The package is advanced by the conveyor underneath a support 64 (see FIG. 1) carrying a pressure actuated cylinder 65 over or above the conveyor. The cylinder 65 has a reciprocable piston rod 66 carrying a downwardly facing cutter 67 which may be a knife blade as illustrated or a heated wire or other element for severing the web 24. It will be appreciated that the advancing motion of the package draws the web 24 forwardly to position a new length of the material underneath the raised separating knives 21.

As the newly separated package advances beneath the cutoff elements 67 to the position shown at 68 in FIG. 1 a lug or tappet 69 on the chain 3 positioned on the far side of the conveyor in FIG. 1 and to the right in FIG. 3 engages and opens the previously described normally closed limit switch 57. This result in breaking the holding circuit through the conductor 63 to the solenoid 60 and deenergize the motor 8. The conveyor is thereby stopped at the proper position just beyond the cutoff element 67. The chain 3 also carries a tappet 70 (see FIGS. 1 and 3) which engages and closes a switch 71 when the package of meat is advanced to cutoff position. Closing of the switch 71 completes a circuit through the conductor 72 and solenoid 73 to the conductor 43 to open the valve 74 and admit fluid pressure to the top of the cylinder 65. This starts the piston rod 66 and cutoff elements 67 downwardly. The cutoff element is moved across the web 24 stretched rearwardly from the rear end of the package and when the piston rod reaches its lower limit of travel a tappet 75 engages and closes the switch 76. The switch 76 is in series with the conductor 72 through the solenoid 77 to reverse the position of the valve 74 and open the valve 78 admitting pressure to the lower end of the cylinder 65 to immediately start the upward retracting motion of the cutoff element 67. As the cutoff element and piston rod 66 reach their upper limit of travel, a tappet 79 strikes and closes a switch 80 connected in series with the conductor 81 and solenoid 82 to shift the

suction or partial vacuum valve 48 to the position illustrated in FIG. 6 and connect to the suction or vacuum means head 17.

The action of the suction or vacuum in the head 17 takes place after the extended end of the film 24 has been severed by the cutoff element 67 and after a series of the support blocks 7 have been moved underneath the raised knives 21 to support the sheet closely adjacent the lower edges of the knives. The conduit 49 opens to the first subdivision in the suction head 17 between the first and second knives at the left end of the head as viewed in FIG. 1. The valve 83 of the valve assembly 20 opening through the second partition plate 19 is subjected to this suction but is held closed by a spring 84 (see FIG. 5) 15 acting on the stem 85 of the valve. The action of the suction is thus constrained through the ports 22 between the first two knives with the result that the film 24 is drawn up snugly around and between the first two knives. The free end of the web 24 moves freely across the blocks 20 to provide the necessary length of film. As the web rises between the first two knives, it seals off the ports 22 thus increasing the intensity of the vacuum or suction in the first sub-chamber 18 to the point where it overcomes the action of the spring 84 biasing the valve 83 closed. The first valve 83 then opens against its biasing force and the suction or vacuum action is repeated in the second sub-chamber to draw the web upwardly between the second and third knives. This action of drawing the web fully and tightly between each adjacent pair of knives 30 progresses successively to the right until all of the knives are closely wrapped with the flexible film and the machine is in condition to perform a succeeding cycle.

The cycle of the machine starting from a condition with the web wrapped around the knives calls for loading 35 of a new package of the product into the loading station 26 and starting of the pressure cylinder 28 by means of the push button 32. When the new package is underneath the knives 21, the push button 40 starts the separating head 17 and knives downwardly, after which the action 40 of the machine is automatic to raise the head, advance the package past the cutoff element while pulling in a new length of the separating web 24. The action of the cutoff element 67 is automatically accomplished, as is the cutting off of the vacuum to permit free retraction 45 of the knives from the treated product and the reestablishment of the suction to draw the new length of web successively around all of the knives. During the time in which the machine is automatically separating one product and advancing and cutting off the separating web, the 50 attendant may be preparing a succeeding package for introduction into the load station 26.

We have illustrated and described one highly practical embodiment of our invention. We have not illustrated or described other embodiments or adaptations, as we 55 believe the embodiment illustrated and described will enable those skilled in the art to embody or adapt our invention as may be desired to meet varying use conditions.

Having thus described the invention, what is claimed 60 as new and desired to secure by Letters Patent is:

1. In a machine for separating a mass product into parallel adjacent strips with flexible sheet separating material folded between adjacent strips and across the upper sides of the strips, a conveyor arranged to support and 65 advance said mass product from a loading station through a separating station to a cutoff station for the sheet, a reciprocable head positioned over said separating station and having a series of separating blades on its lower face, means forming a sub-divided suction chamber in said 70 head with sub-divisions communicating with the space between each pair of adjacent blades, a suction connection opening to the sub-division between the first two blades, valves positioned between the sub-divisions to open toward said suction connection and affording communication between adjacent sub-divisions and biased by 75

springs toward closed position, support means arranged to support a supply roll of the flexible sheet material and direct the end thereof underneath said blades from the rear end thereof relative to the advancing motion of said conveyor, a first drive element consisting of a reciprocable piston rod arranged to advance said conveyor from said loading station to underneath said head, a second drive element having an overrunning connection to said conveyor, a cutoff element positioned to sever said sheet at the rear edge of said separating station, automatic control means connected upon initiation of downward motion of said head to successively disconnect said suction connection, elevate said head at the completion of its downward motion, energize said second drive element to advance said conveyor from said head to cutoff position, stop said second drive element, reciprocate said cutoff element, reconnect said suction connection and retract said first drive element, first manual control means connected to advance said first drive element, and other manual control means connected to initiate downward movement of said head, said last control means including a safety switch closed by movement of said mass product to said separating station, said first manual control means including a second safety switch closed by movement of said head to raised position.

2. In a machine for separating a mass product into parallel adjacent strips with sheet separating material folded between adjacent strips and across the upper sides of the strips, a conveyor arranged to support and advance said mass from a loading station through a separating station to a cutoff station for the sheet, a reciprocable head positioned over said separating station and having a series of blades on its lower face, means forming a sub-divided suction chamber in said head with sub-divisions communicating with the space between each pair of adjacent blades, a suction connection opening to the sub-division between the first two blades, valves positioned between the sub-divisions to open toward said suction connection and affording communication between adjacent sub-divisions and yieldingly biased toward closed position, support means arranged to support a supply roll of a flexible sheet and direct the end thereof underneath said blades from the rear end thereof relative to the advancing motion of said conveyor, a first drive element consisting of a reciprocable piston rod arranged to advance said conveyor from said loading station to underneath said head, a second drive element having an overrunning connection to said conveyor, a cutoff element positioned to sever said sheet at the rear edge of said cutoff station, and automatic control means connected upon initiation of downward motion of said head to successively disconnect said suction connection, elevate said head at the completion of its downward motion, energize said second drive element to advance said conveyor from said head to cutoff position, stop said second drive element, reciprocate said cutoff element, reconnect said suction connection and retract said first drive element.

3. In a machine for separating a mass product into parallel strips with a sheet of separating material folded between adjacent strips and across the upper sides of the strips, a conveyor arranged to support and advance said mass from a loading station through a separating station to a cutoff station for the sheet, a reciprocable head positioned over said separating station and having a series of blades on its lower face, means forming a sub-divided suction chamber in said head with sub-divisions communicating with the space between each pair of adjacent blades, a suction connection opening to the sub-division between the first two blades, valves positioned between the sub-divisions to open toward said suction connection and affording communication between adjacent sub-divisions and biased toward closed position, support means arranged to support a supply roll of a sheet material and direct the end of the material underneath said blades from the rear end thereof relative to the advancing mo-

tion of said conveyor, drive means arranged to advance said conveyor, a cutoff element positioned to sever said sheet material at the rear edge of said cutoff station, and automatic control means connected upon initiation of downward motion of said head to successively disconnect said suction connection, elevate said head at the completion of its downward motion, advance said conveyor from said head to cutoff position, stop said conveyor, reciprocate said cutoff element, and reconnect said suction connection, said cutoff station being advanced beyond said head by a distance equal to the length of sheet necessary to lap the surfaces of said knives and the surfaces therebetween.

4. In a machine for separating a mass of material into strips with separating sheet material folded between adjacent strips and across the upper sides of the strips, a conveyor arranged to support and advance said mass through a separating station to a cutoff station for the sheet, a reciprocable head positioned over said separating station and having a series of blades on its lower face, means forming a sub-divided suction chamber on said head with sub-divisions communicating with the space between each pair of adjacent blades, a suction connection opening to the sub-division between two blades, valves positioned and opening between said sub-divisions to open toward said suction connection and biased toward closed position, support means arranged on said conveyor between the mass supporting portions thereof to support a sheet of separating material adjacent the lower edges of

30 said blades, a support for a supply roll of the flexible sheet material arranged to direct the sheet underneath said blades from the rear end thereof relative to the advancing motion of said conveyor, drive means arranged to advance said conveyor, a cutoff element positioned to sever said sheet at the rear edge of said cutoff station, and control means connected to initiate downward motion of said head, disconnect said suction connection, elevate said head at the completion of its downward motion, advance said conveyor from said head to cutoff position, reciprocate said cutoff element, and reconnect said suction connection, said cutoff station being advanced beyond said head by a distance as great as the length of sheet necessary to lap the surfaces of said blades and the surfaces therebetween.

5. In a machine for separating a mass of material into strips with sheet material folded between adjacent strips and across the upper sides of the strips, a conveyor arranged to support and advance said mass through a separating station to a cutoff station for the sheet, a reciprocable head positioned over said separating station and having a series of blades on its lower face, means forming a sub-divided suction chamber on said head with sub-divisions communicating with the space between each pair of adjacent blades, a suction connection opening to

55 the sub-division between two blades, valves positioned and opening between the said sub-divisions to open toward said suction connection and biased toward closed position, support means arranged on said conveyor between the mass supporting portions thereof to support a sheet of separating material adjacent the lower edges of said blades, a support for a supply roll of said material arranged to direct the material underneath said blades from the rear end thereof relative to the advancing motion of said conveyor, drive means arranged to advance said conveyor, a cutoff element positioned to sever said sheet at the rear edge of said cutoff station, and control means connected to initiate downward motion of said head, disconnect said suction connection, elevate said head at the completion of its downward motion, advance

60 said conveyor, a cutoff element positioned to sever said sheet at the rear edge of said cutoff station, and control means connected to initiate downward motion of said head, disconnect said suction connection, elevate said head at the completion of its downward motion, advance said conveyor from said head to cutoff position, reciprocate said cutoff element, and reconnect said suction connection.

6. In a machine for separating a mass of material into strips with separating sheet material folded between adjacent strips and across the upper sides of the strips,

means arranged to support and advance said mass through a separating station to a cutoff station for the sheet material, a reciprocable head positioned over said separating station and having a series of blades on its lower face, means forming a sub-divided suction chamber on said head with sub-divisions communicating with the space between each pair of adjacent blades, a suction connection opening to the sub-division between two blades, valves positioned and opening between the said sub-divisions to open toward said suction connection and biased toward closed position, support means arranged to support a film of separating material adjacent the lower edges of said blades, a support for a supply roll of the sheet material arranged to direct it underneath said blades from the rear thereof relative to the advancing motion of said support means, drive means arranged to advance said support means, a cutoff element positioned to sever said sheet at the rear edge of said cutoff station, and control means connected to initiate downward motion of said head, disconnect said suction connection, elevate said head at the completion of its downward motion, advance said means for supporting said mass from said head to cutoff position, reciprocate said cutoff element, and re-connect said suction connection.

7. An apparatus of the class described comprising a work conveyor, means for driving said conveyor step by step, a chambered head member disposed above and reciprocatingly mounted relative to said conveyor and in timed relation to the actuation thereof, said head member having a plurality of laterally extending and downwardly projecting parallel blades of uniform width and spacing spaced longitudinally relative to said conveyor, means for positioning a flexible sheet between said conveyor and head member and closely adjacent to the lower edges of the blades, the chamber of said head member having transverse partitions therein disposed in vertical alignment with the blades and providing a series of suction chambers, said partitions having chamber connecting ports therein provided with suction opened spring seated valves, said head member having inlet openings therein between said blades opening to said suction chambers, suction means connected to the first of said series of suction chambers, and means for actuating said sheet positioning means and suction control means in timed relation to each other and to said conveyor and head member actuating means.

8. An apparatus of the class described comprising a work conveyor, means for driving said conveyor step by step, a chambered head member disposed above and reciprocatingly mounted relative to said conveyor and in timed relation to the actuation thereof, said head member having a plurality of laterally extending and downwardly projecting blades spaced longitudinally relative to said conveyor, means for positioning a flexible sheet between said conveyor and head member, the chamber of said head member having transverse partitions therein forming adjacent suction chambers, said partitions having chamber connecting ports therein provided with suction opened spring seated valves, said head member having inlet openings therein between said blades opening to said suction chambers, suction controlled means connected to the first of said series of suction chambers, and means for actuating said sheet positioning means and suction control means in timed relation to each other and to said conveyor and head member actuating means.

9. An apparatus of the class described comprising a work support, a chambered head member mounted for reciprocating movement relative to said work support, said head member having a plurality of laterally spaced downwardly projecting parallel blades of uniform width and spacing, means for positioning a flexible sheet between said work support and head member and closely adjacent to the lower edges of the blades, the chamber of said head member having transverse partitions therein disposed in vertical alignment with the blades and providing a series

5 of suction chambers, said partitions having chamber connecting ports therein provided with suction opened spring seated valves, said head member having inlet openings to said suction chambers disposed between said blades, suction means connected to the first of said series of suction chambers, and means for actuating said sheet positioning means and suction means in timed relation to each other.

10. An apparatus of the class described comprising a work support, a chambered head member mounted for reciprocating movement relative to said work support, said head member having a plurality of laterally spaced downwardly projecting blades, means for positioning a flexible sheet between said work support and head member, the chamber of said head member having transverse partitions therein providing a series of suction chambers, said partitions having chamber connecting ports therein provided with suction opened valves, said head member having inlet openings to said suction chambers disposed between said blades, suction means connected to the first 15 of said series of suction chambers, and means for actuating said sheet positioning means and suction means in timed relation to each other.

11. An apparatus of the class described comprising a work support, a chambered head member mounted for reciprocating movement relative to said work support, said head member having a plurality of laterally spaced downwardly projecting parallel blades of uniform width and spacing, said work support and head member being spaced when the head member is in retracted position to receive the work and a flexible sheet between the work and the blades on the head member, the chamber of said head member having transverse partitions therein disposed in vertical alignment with the blades and providing a series of suction chambers, said partitions having chamber connecting ports therein provided with suction opened spring seated valves, said head member having inlet openings to said suction chambers disposed between said blades, and suction means connected to the first of said series of suction chambers.

12. An apparatus of the class described comprising a work support, a chambered head member mounted for reciprocating movement relative to said work support, said head member having a plurality of laterally spaced downwardly projecting blades, said work support and head member being spaced when the head member is in retracted position to receive the work and a flexible sheet between the work and the blades on the head member, the chamber of said head member having transverse partitions therein providing a series of suction chambers, said partitions having chamber connecting ports therein provided with suction opened valves, said head member having inlet openings to said suction chambers disposed between said blades, and suction means connected to the first of said series of suction chambers.

13. An apparatus of the class described comprising a work support, a head member mounted for reciprocating movement relative to said work support, said head member having a plurality of laterally spaced downwardly projecting parallel blades, said work support and head member being spaced when the head member is in retracted position to receive the work and a flexible sheet between the work and the blades on the head member, said head member having a series of suction chambers thereon, inlet openings to said suction chambers disposed between said blades, and suction means connected to said series of suction chambers for producing suction therein successively whereby said sheet is successively wrapped around said blades.

14. An apparatus of the class described comprising a work conveyor, means for driving said conveyor step by step, a head member disposed above and reciprocatingly mounted relative to said conveyor and actuated in timed relation to the actuation thereof, said head member having a plurality of laterally extending and downwardly projecting blades spaced longitudinally relative to said

conveyor, means for positioning a flexible sheet between said conveyor and said head member operatively associated with said conveyor whereby a sheet is positioned between the head member and a piece of work on a work conveyor, said head member having a series of suction chambers therein and having inlet openings to the chambers disposed between the blades, suction means connected to said series of suction chambers for producing suction therein successively whereby the sheet is wrapped around the blades successively, and control means for said suction means having timed actuation with the actuation of said conveyor and said head member.

15. An apparatus of the class described comprising a work conveyor, means for driving said conveyor step by step, a head member disposed above and reciprocatingly mounted relative to said conveyor and actuated in timed relation to the actuation thereof, said head member having a plurality of laterally extending and downwardly projecting blades spaced longitudinally relative to said conveyor, said head member having a series of suction chambers therein and having inlet openings to the chambers disposed between the blades, suction means connected to said series of suction chambers for producing suction therein successively whereby the sheet is wrapped around

10
15

the blades successively, and control means for said suction means having timed actuation with the actuation of said conveyor and said head member.

16. An apparatus of the class described comprising a work conveyor, means for driving said conveyor step by step, a head member disposed above and reciprocatingly mounted relative to said conveyor in timed relation to the actuation thereof, said head member having a plurality of laterally extending and downwardly projecting blades spaced longitudinally relative to said conveyor, said head member having a series of suction chambers therein and inlet openings to the chambers disposed between the blades, suction means connected to said series of suction chambers for producing suction therein successively whereby a sheet positioned between the work successively on the conveyor and said head member is wrapped around the blades, and control means for said suction means having timed actuation with the actuation of said conveyor and said head member.
